UNITED STATES PATENT OFFICE.

HIRAM W. HAYDEN, OF WATERBURY, CONNECTICUT, ASSIGNOR TO THE HOLMES, BOOTH & HAYDENS, OF SAME PLACE.

DESIGN FOR A FLAME-SPREADER FOR LAMPS.

SPECIFICATION forming part of Design No. 23,809, dated November 13, 1894.

Application filed December 21, 1892. Serial No. 455,946. Term of patent 7 years.

To all whom it may concern:

Be it known that I, HIRAM W. HAYDEN, of Waterbury, in the county of New Haven and State of Connecticut, have invented and produced a new and original Design for Thimbles or Flame-Spreaders for Lamps, of which the following is a specification.

This design is applied to a specific article known in the lamp trade as a thimble, or flame spreader, and is to be placed in connection with the wick tube of any central draft lamp.

In the accompanying drawings, Figure 1 is a side elevation of a thimble or flame spreader, showing my design. Fig. 2 is a vertical longitudinal section thereof.

The leading feature of my design consists in a plain band or annular surface having an inward and an outward curve in the vertical direction, and arranged between two annular perforated portions.

Referring by letter to the drawings A des-

ignates the thimble or flame spreader. It has a plain annular lower surface a ; an annular perforated portion a' , above the surface a , which is slightly concaved vertically; a plain band or annular surface a^2 , above the perforated portion a' , which, in a vertical direction is turned inward and then outward; an annular perforated portion a^3 , above the plain band or annular surface a^2 , shown, in a vertical direction, as bent inward, then inward and then outward, and a closed top a^4 .

What I claim is—

The design for a thimble or flame spreader for lamps substantially as shown and described.

In testimony whereof I have signed my name to this specification in the presence of two subscribing witnesses.

HIRAM W. HAYDEN.
